Carl Stouffer

ATTORNEY.

UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

Application filed August 15, 1924. Serial No. 732,315.

To all whom it may concern:

Be it known that I, RICHARD M. VAN VALKENBURGH, a citizen of the United States, residing at Kansas City, in the county of Jackson and State of Missouri, have invented certain new and useful Improvements in Loose-Leaf Binders, of which the following is a complete specification.

This invention relates to certain new, useful and highly desirable improvements in loose-leaf binders, and pertains especially to the post gripping and actuating means therefor located within the hollow clamping member of a binder of the post type.

15 The primary object of the invention is to provide a post gripping means and actuating means therefor in which the parts may all be quickly assembled into a unit before inserting into the hollow clamping member.

20 A further object of the invention is to provide means for actuating the gripping plates which is positive in its action of locking and unlocking the binder, and which maintains pressure on the gripping plates at all times.

25 A still further object of this invention is the provision of a supporting means for the working parts of the binder which permits of assembling said parts before inserting to the working position.

30 An even further object of the invention is to provide means for locking and unlocking post binders of this type that is exceedingly easy to assemble, has but few parts, will not get out of order after once assembled, and forms a structure of great strength and durability.

Further and other objects will be later set forth and manifested in the course of the following description.

40 In the drawings:

Figure 1 is a vertical central section of a loose-leaf clamping member with the invention in place and used in connection with an ordinary post binder.

45 Fig. 2 is a horizontal section of the same taken on line II-II of Fig. 1.

Fig. 3 is an enlarged fragmentary sectional view of the invention, similar to Fig. 1, showing the device in both the locked and unlocked positions.

50 Fig. 4 is a cross section of the same taken on line IV-IV of Fig. 3.

Fig. 5 is a perspective view of the working parts of the invention with the actuati-

ing spring member raised out of normal position.

Fig. 6 is another cross section of the hollow clamping member containing the invention, taken on line VI-VI of Fig. 3 and showing the gripping plate in the unlocked or raised position.

Referring to the drawings in detail, wherein similar reference characters refer to like parts throughout the several views, and wherein the invention is shown in use with a binder of the ordinary post type having a clamping member 7 to which posts 8 are rigidly attached.

The leaves 9 are placed on posts 8 in the ordinary manner, and hollow clamping member 10, which contains the securing means, is then positioned by causing posts 8 to enter apertures 11 provided for that purpose. After pressing member 10 against leaves 9, gripping plates 12, having perforations 13, clutch posts 8 in the manner shown to preclude its removal until plates 12 are released.

To accomplish this action and result in the most desirable way and with the minimum number of parts, as well as to allow quick assembling before inserting to the working position, a channel 14, preferably formed of sheet metal, may be cut substantially the length of member 10 and notched near the ends as at 15 to form means for pivotally supporting the gripping plates 12, which are provided with oppositely disposed lugs 16 for engaging notches 15. When the assembled unit is inserted into hollow clamping member 10, lugs 16 are confined and positively retained in notches 15 by the upper wall of member 10, which is in contact with the upper edges of the side walls of channel 14 throughout its entire length.

These gripping plates 12 have an inclined portion 17 through which pass perforation 13 which aligns with hole 18 to allow the unobstructed passage of post 8. Lugs 16 are positioned at the edges of plate 12 and at the meeting line of inclined portion 17 in the manner clearly shown in Fig. 5.

In the present invention, any necessary spring pressure is present in the actuating bar or resilient releasing member 19 which is always in contact with the face of gripping plates 12. This releasing member 19 may be arcuate in shape and formed with its

2

ends notched or bifurcated as at 20 to straddle posts 8. A button 21, rigidly attached near the center and passing upwardly through member 10 is employed by the operator to impart reciprocating motion to releasing member 19 when operating the device. Pressure is always exerted upon plate 12, since member 19 must be depressed to enter clamping member 10, always to be maintained in this condition with its central portion in sliding contact with the inner surface of said member 10. A guide or stop lug 22 is pressed from releasing member 19 which rests against one of the gripping plates 12 (Fig. 3).

Operation.

To assemble the device, channel 14 is first fitted with gripping plates 12, as illustrated in Fig. 5, releasing member 19 is placed with its bifurcated ends bearing upon the face of plates 12 and lug 22 resting against the end of one. After depressing member 19, the device may be inserted 25 into hollow clamping member 10 until holes 13 and 18 register with holes 11. Button 21 is inserted and riveted through openings 23, left for that purpose, after which the channel may be riveted or welded to member 10 30 to secure the unit in place and against slipping.

When first inserted, the members are in the locked position as shown in full lines in Figs. 1, 2, 3 and 4, and when posts 8 are gripped by plates 12, member 19 retains a pressure which is positive and most effective. To release the grip, it is only necessary to slide releasing member 19 to the position shown in dotted lines in Fig. 3. This 40 movement removes the downward pressure exerted by the ends of the releasing member from inclined portion 17 of plates 12 and places it back of the pivotal point formed by lugs 16, an operation which snaps 45 inclined portion 17 of plates 12 up to a substantially horizontal position with its edges in engagement with the inner surface of member 10, as shown in Fig. 6. The device may now be withdrawn from the posts.

50 *I claim:*

1. In a loose-leaf binder, a pair of leaf-holding posts, a hollow clamping member provided with apertures for receiving the posts, post-gripping plates mounted within said hollow clamping member and actuating means for slidably engaging said gripping plates, said actuating means having a pressed out lug adjacent one end and engaging an edge of one of said gripping plates for retaining said actuating means in position during assembling, substantially as set forth.

60 2. In a post-gripping means for a loose-leaf binder, adapted to be inserted as a unit 65 in the hollow clamping member thereof,

comprising a channel having notches in its side walls, post-gripping plates mounted in said notches and an actuator for said gripping plates, said channel having the upper edges of its side walls in contact with the upper wall of said clamping member for the purpose set forth.

3. In a post-gripping means for a loose-leaf binder, adapted to be inserted as a unit in the hollow clamping member thereof, comprising a channel having notches in its side walls, post-gripping plates having outwardly extending lugs pivotally seated in said notches with the body portion thereof confined between the said walls of said channel and an actuator for said gripping plates, said channel having the upper edges of each side wall in contact with said hollow clamping member for maintaining said gripping plate lugs in their seated position.

4. In a loose-leaf binder, a pair of leaf-holding posts, a hollow clamping member provided with apertures for receiving the posts, a channel having holes registering with said apertures and notches in the side walls at the top thereof, gripping plates provided with a hole concentric with said channel hole and clamping member aperture and having lugs seated in said notches and actuating means for said gripping plates having an assembling lug, said notches being closed at the top to confine said gripping plate lug by the upper wall of said hollow clamping member.

5. In a loose-leaf binder, the combination with a pair of leaf-holding posts and a hollow clamping member provided with apertures for receiving said posts, of a post-gripping means, an actuator therefor and means for supporting said gripping and actuating means in their related position before inserting the same into said hollow clamping member.

6. In a loose-leaf binder, the combination with a pair of leaf-holding posts and a hollow clamping member provided with apertures for receiving said posts, of a perforated gripping means for each post, an actuator therefor and means for assembling the same into their related position before inserting the same into said hollow clamping member comprising a channel having holes in the base and notches in the side walls thereof, said notches adapted to hold each post-gripping means with its perforation concentric with the holes in said channel base.

7. In a loose-leaf binder, the combination with a pair of leaf-holding posts and a hollow clamping member provided with apertures for receiving said posts, of a perforated gripping means for each post having horizontally disposed lugs projecting from the sides thereof, an actuator for said gripping means having a downwardly extending

- assembling lug for engaging one of said gripping means, and means for assembling the same into operative relation before inserting the same into said hollow clamping member, comprising a channel having holes in the base and notches in the side walls thereof, the lugs of said gripping means being seated in said notches and confined therein by the walls of said hollow clamping member when said channel is inserted therein to a point where the holes of said channel and the gripping means perforation are concentric with said clamping member apertures.
- 15 8. In a loose-leaf binder, the combination with a pair of leaf-holding posts, a hollow clamping member provided with apertures for receiving said posts, a perforated gripping means for each post and an actuator therefor having a downwardly extending assembling lug, of means for supporting said gripping means and actuator in

operative position comprising a channel having holes in the base and notches in the side walls thereof, whereby said gripping member and actuator is completely assembled before inserting the same into said hollow clamping member.

9. An assembling unit for post-gripping and actuating means, for loose-leaf binders 30 having a hollow clamping member, comprising a channel of a length equal to the length of said hollow clamping member and having holes in the bottom thereof, means carried by the side walls of said channel for 35 pivotally supporting a post-gripping plate, said channel adapted to slide into said hollow clamping member and carry said post-gripping plate into operative position, substantially as set forth. 40

In testimony whereof I hereunto set my hand and seal this 13th day of August, 1924.

RICHARD M. VAN VALKENBURGH.
